UNITED STATES PATENT OFFICE.

WILLIAM D. GHARKY, OF PHILADELPHIA, PENNSYLVANIA, ASSIGNOR TO
THE SUN ELECTRIC MANUFACTURING COMPANY, OF NEW JERSEY.

DESIGN FOR A TELEPHONE-INSTRUMENT WALL-CASE.

SPECIFICATION forming part of Design No. 32,597, dated April 24, 1900.

Application filed February 17, 1899. Serial No. 705,907. Term of patent 14 years.

To all whom it may concern:

Be it known that I, WILLIAM D. GHARKY, a citizen of the United States, residing at Philadelphia, in the county of Philadelphia and State of Pennsylvania, have invented and produced a new and original Design for a Telephone-Instrument Wall-Case, of which the following is a specification, reference being had to the accompanying drawings, forming a part hereof.

Figure 1 is a front view of a telephone-instrument wall-case, showing my new design. Fig. 2 is a side view thereof.

As shown in the drawings, the leading or material feature of my design consists of the rectangular box A, having a body part b with its base expanding gracefully into a flange a.

Projecting from the body are the twin lugs or pieces c, which expand and merge at their base into the front of the box, as shown. 20 The contour of the case is softened by the rounded corners and its face and sides are plain.

The general appearance of the design as a whole is that of simplicity and grace. 25

Having described my invention, what I claim as new, and desire to secure by Letters Patent, is—

The design for a telephone-instrument wall-case, as herein shown and described.

WILLIAM D. GHARKY.
